UNITED STATES PATENT OFFICE.

THEODORE G. THOMAS, OF HOUSTON, TEXAS.

SIGNAL-LIGHT.

1,334,191.

Specification of Letters Patent. Patented Mar. 16, 1920.

Application filed May 19, 1919. Serial No. 298,026.

To all whom it may concern:

Be it known that I, THEODORE G. THOMAS, a citizen of the United States, residing at Houston, in the county of Harris and State of Texas, have invented new and useful Improvements in Signal-Lights, of which the following is a specification.

This invention relates to improvements in signaling means and the principal object 10 of the invention is to provide a lantern or other lamp with a signal device so arranged that it will be plainly visible when the lantern is held in one position, but will be invisible when the lantern is held in another 15 position as only the thin edge of the device will be exposed.

Another object of the invention is to provide means for shielding the light and reflecting the same upon the signal device 20 when said device is in exposed position and which will permit the light to be fully exposed when the lantern is held in the other position.

Still another object of the invention is 25 to provide a handle so arranged that it will indicate to the person holding the lantern the position of the signal device.

The invention also consists in certain 30 other features of construction and in the combination and arrangement of the several parts, to be hereinafter fully described, illustrated in the accompanying drawings and specifically pointed out in the appended claims.

35 In describing my invention in detail, reference will be had to the accompanying drawings wherein like characters denote like or corresponding parts throughout the several views, and in which:—

40 Figure 1 is an elevation of the invention; Fig. 2 is a like view, but taken at right angles to Fig. 1;

Fig. 3 is a sectional view;

45 Figs. 4 and 5 are perspective views of the signals which may be used with the lantern;

Figs. 6 and 7 are views of the device applied to a signal post.

In these views 1 indicates the bottom 50 frame of the lantern which carries the reservoir 2 for containing the fuel for the burners 3. 4 indicates the hinged frame which carries the globe 5. As shown, the frame and globe are of substantially square shape in cross section so as to facilitate the opera-

tion of the device. 6 indicates the handle secured to the top of the frame 4 in a rigid manner.

The reservoir has secured to its top a pair of shields 7 which are diametrically arranged, one in front of each burner so that the light from the burners will be obstructed from opposing sides of the lantern while it will be unobstructed from the other two sides. Centrally arranged on the top of the reservoir between the burners, is the signal device 8. This device is detachably connected with the reservoir by having its base 9 provided with the downwardly depending legs 10 which engage the slots 11 in the top 70 of said reservoir, said slots being formed in the projecting edges of the top so that said slots will not communicate with the interior of the reservoir. I may make the body of the device in the form of a cross, as shown 75 in Fig. 4, or the device may be made as shown in Fig. 5 which shows a plate carrying the word "Stop". If desired, however, I may make the body of the device of a solid plate and paint a cross thereon. When 80 desired, one of the signal devices may be replaced by the other.

It will thus be seen that the shield 7 will reflect the light from the burners onto the signal device while at the same time obstructing the light from two sides of the lantern so that persons looking at the lantern from these two sides will clearly see the cross or other signal without seeing the lights. Persons looking at the lantern from 90 the other two sides will see the two lights, but will not see the signal as only the thin edge of the signal is exposed at these two sides and this cannot be seen unless a person is close to the lantern.

The parts are so arranged that the signal device extends in the same plane as the handle so that the operator can tell by the way he is holding the handle, the position 95 of the signal is in without looking at the signal.

If desired, the invention may be applied to the well-known form of post lamp, as shown in Fig. 6. In this figure, the supporting post is shown at 12 and the lamp 105 at 13. This lamp is turned by the handle 14 which is connected with the inner post which has secured to its top the inner parts of the lamp.

I may use my device on the automatic 110

signals worked by the train or the device may be used on the signals which are operated from watch towers and the like.

5 I may color some of the sides of the lantern to use the same as the ordinary signal lanterns now in use and the red cross may be painted on the sides of the globe.

10 It will be seen that when the device is used at the intersection of a crossing of two streets the signal will appear from opposite sides of the device while the other two sides will give a clear signal so that the traffic coming in all four directions will be given the signal at the same time.

15 Furthermore, it will be seen that when my improved signal lamp is used at the intersection of the highway and the railway and the lamp is turned so as to indicate that the highway is open for traffic, the engineer of 20 an approaching train will be in a position to see the danger signal displayed by the illuminated red cross thereby cautioning the engineer that he is approaching the highway that is open to traffic so that he may control 25 his train accordingly.

It is thought from the foregoing description that the advantages and novel features of my invention will be readily apparent.

I desire it to be understood that I may 30 make changes in the construction and in the combination and arrangement of the several parts, provided that such changes fall within the scope of the appended claims.

What I claim is:—

35 1. A device of the class described com-

prising a transparent casing, a lighting medium therein, a flat upright signal member of opaque material mounted within the casing to one side of said medium, a combined shield and reflector on the opposite 40 side of said lighting medium for obstructing the light therefrom in one direction and reflecting said light upon the signal member and means for turning the casing to expose either the broad side or the thin edge 45 of the signal member.

2. The combination with a lantern and its burner, of a globe for the lantern of substantially rectangular form in cross section, a flat upright signal member mounted 50 within the globe between the burner and one side of the globe, a shield located on the opposite side of the burner and between the burner and one side of the globe and a rigid handle for the lamp lying in the same 55 plane as the signal.

3. A device of the class described comprising a lantern of substantially rectangular form, a reservoir for the lantern, a pair of burners on said reservoir, a flat upright 60 signal in the shape of a cross located on said reservoir between the burners with its broad sides facing two sides of the lantern, a shield located in front of each burner for reflecting the light upon the signal and a 65 rigid handle on the lantern extending in the same direction as the signal.

In testimony whereof I affix my signature.

THEODORE G. THOMAS.
